(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view with the slid-up rear body thereof;

FIG. 9 is a front view with the slid-up rear body thereof;

FIG. 10 is a rear view with the slid-up rear body thereof;

FIG. 11 is a left side view with the slid-up rear body thereof;

FIG. 12 is a right side view with the slid-up rear body thereof;

FIG. 13 is a top view with the slid-up rear body thereof; and,

FIG. 14 is a bottom view with the slid-up rear body thereof.

The broken lines shown in the figures that are immediately adjacent to the shaded areas and define unshaded regions represent the bounds of the claim. The broken lines form no part of the claimed design.

1 Claim, 12 Drawing Sheets
